ANTENNA SYSTEM

Walter Max Hahnemann, Berlin, Germany, assignor to C. Lorenz Aktiengesellschaft, Berlin-Tempelhof, Lorenzweg, Germany, a company

Application June 22, 1938, Serial No. 215,138
In Germany May 15, 1937

7 Claims. (Cl. 250—11)

The present invention relates to antenna systems and has for its object to eliminate the interfering silent zones of the radiation diagrams produced by such systems.

5 The radiation diagram obtained in connection with antenna systems provided on towers at a certain distance above the earth's surface represents a number of "leaves" which are set up on account of the interference between the direct 10 radiation from the antenna and by the radiation reflected from the earth's surface.

The invention consists in certain features of novelty which are disclosed in the following description and pointed out in the appended claims, 15 reference being made to the accompanying drawing, in which:

Fig. 1 diagrammatically illustrates the radiation pattern of a known antenna system; Fig. 2 is a diagrammatic representation in details of a radiation pattern obtained according to the invention; Fig. 3 shows the resulting effective radiation pattern according to the invention; while Fig. 4 schematically illustrates the antenna system according to the invention.

25 The radiation diagram shown in Fig. 1 shows the "leaves" above referred to. The number and the form of these leaves and the intermediate silent zones depend upon the operating wavelength and the height of the antenna system above the earth's surface. The ratio between these magnitudes is particularly high 30 within the range of ultra short waves so that a very great number of leaves are obtained. Such radiation diagrams are disadvantageous in many respects, for instance, in connection with wireless communication with aircrafts since the great 35 number of silent zones is troublesome on approaching the transmitter. This disadvantage is particularly accentuated in cases that such transmitters are intended for use in wireless 40 navigation.

The invention has for its object to eliminate the troublesome silent zones of a radiation diagram. The invention proposes the application 45 of a second radiating structure the radiation pattern of which is so formed that its maxima are located where the minima of the actual antenna radiation pattern are located.

It has already been mentioned that the number 50 and the shape of the leaves and of the silent zones may be adjusted by correspondingly dimensioning the height of an antenna system above the earth's surface. The height of the two radiating structures is so dimensioned according to a further feature of the invention

that the desired overlapping between the two radiation patterns is secured. The second additional radiation structure is thus placed either above or below the actual radiating system.

Fig. 2 illustrates two radiation patterns in which the individual leaves are so dimensioned with respect to their number and their shape that the minima of one radiation pattern coincide with the maximum of each leaf of the second radiation pattern. One of these patterns is indicated in the Fig. 2 by means of thick lines while the second pattern is hatched. It is thus obvious that the original maxima and minima of the radiation pattern have been equalized so that a useful diagram is obtained as shown in Fig. 3.

The coupling between the two antenna structures arranged one above the other may be accomplished in different manners. Both antenna structures may be fed over energy lines from a transmitter common to both antenna structures. It is also possible to feed one antenna structure only from the transmitter, while coupling the second antenna structure by means of radiation. On the other hand, a galvanic, an inductive or a capacitive coupling may be employed.

One embodiment of the novel antenna arrangement is illustrated in Fig. 4. A tower 1 carries one antenna system 2 and a second antenna system 3 arranged below the first mentioned system. The heights above the earth's surface at which the two systems are arranged are so dimensioned that the minima of one radiation pattern coincide with the maxima of the second system. The main system 2 is fed by the transmitter S over an energy line 4. The additional system 3 is coupled to the system 2 either by means of radiation or galvanically, inductively or capacitively through the coupling device 5.

In cases that the antenna arrangement above described shall be employed for aircraft navigation, alternately keyed reflectors may be allotted to the antenna structures 2 and 3, whereby the reflectors may be coupled with one another in any known manner.

The compensation of the silent zones is not necessarily to be accomplished by virtue of a second antenna arrangement. For instance, it is possible to provide means such as metal sheets, wire meshes and the like so as to produce the desired interference with respect to the silent zones.

What is claimed is:

1. An antenna system comprising a first antenna for producing a radiation pattern having a plurality of maximum and minimum points in a vertical plane, and a second antenna for producing a pattern having a similar plurality of maximum and minimum points in a vertical plane, said antennae being spaced above the earth different distances such that the maximum points of the radiation pattern from said first antenna coincide with the minimum points of said radiation pattern from said second antenna.
2. An antenna arrangement comprising two antenna systems for producing radiation patterns each having a plurality of maximum and minimum points in vertical planes, said antenna systems being arranged one above the other and spaced above the earth distances such that the minima of the radiation pattern produced by one antenna system coincide with the maxima of the radiation pattern produced by the second antenna system.
3. An antenna arrangement comprising two antenna systems for producing radiation patterns each having a plurality of maximum and minimum points in vertical planes, said antenna systems being arranged one above the other and above the surface of the earth so that the minima of the radiation pattern produced by one antenna system coincide with the maxima of the radiation pattern produced by the second antenna system, and an oscillation generator common to both antenna systems for feeding these systems.
4. An antenna arrangement comprising two antenna systems for producing radiation patterns each having a plurality of maximum and minimum points in vertical planes, said antenna systems being arranged one above the other and spaced above the earth such distances that the minima of the radiation pattern produced by one antenna system coincide with the maxima of the radiation pattern produced by the second antenna system, an oscillation generator for feeding one of said antenna systems, and means for coupling the other antenna system to the fed antenna system.
5. An antenna system for producing a radiation pattern relatively free from field strength variations in the vertical plane, comprising an antenna spaced above the earth for producing a radiation pattern inherently having a plurality of maximum and minimum zones in a vertical plane, and additional conductive means arranged below said antenna for equalizing radiation in the minimum zones intermediate said radiation pattern maximum zones.
6. An antenna arrangement for the purpose of navigating aircraft, comprising two antenna systems for producing radiation patterns each having a plurality of maximum and minimum points in vertical planes, said antenna systems being arranged one above the other and spaced above the earth such distances that the minima of the radiation pattern produced by one antenna system coincide with the maxima of the radiation pattern produced by the second antenna system, an oscillation generator common to both antenna systems for feeding these systems, alternately keyed reflectors arranged on either side of both antenna systems, and means for coupling said reflectors to one another.
7. An arrangement for the purpose of navigating aircraft, comprising two antenna systems for producing radiation patterns each having a plurality of maximum and minimum points in vertical planes, said antenna systems being arranged one above the other and spaced above the surface of the earth a distance such that the minima of the radiation pattern produced by one antenna system coincide with the maxima of the radiation pattern produced by the second antenna system, an oscillation generator adapted to feed one of said antenna systems, means for coupling the other antenna system to the fed antenna system, alternately keyed reflectors arranged on either side of both antenna systems, and means for coupling said reflectors to one another.

WALTER MAX HAHNEMANN.
